UNITED STATES PATENT OFFICE

166,031

CHRISTMAS TREE ORNAMENT OR THE LIKE

Mary S. Douglas, Barrington, R. I., assignor to
 E. R. Bassett Corp., a corporation of Rhode Island

Application October 8, 1948, Serial No. 149,034

Term of patent 7 years

(Cl. D29—1)

To all whom it may concern:

Be it known that I, Mary S. Douglas, a citizen of the United States of America, residing at Barrington, county of Providence, State of Rhode Island, have invented a new, original, and ornamental Design for a Christmas Tree Ornament or the like, of which the following is a specification, reference being had to the accompanying drawing, forming a part thereof.

Fig. 1 is a front view of a Christmas tree ornament or the like, showing my new design;

Fig. 2 is a rear view; and

Fig. 3 is an edge view thereof;

Fig. 4 is a sectional view taken substantially along line 4—4 of Fig. 1.

The drawing has been shaded to show contrasting appearance. The dot and dash lines shown in Figure 3 are for illustrative purposes only.

I claim:

The ornamental design for a Christmas tree ornament or the like, substantially as shown and described.

MARY S. DOUGLAS.
